UNITED STATES PATENT OFFICE.

EDISON W. HART, OF MASSILLON, OHIO, ASSIGNOR TO THE RELIANCE MANUFACTURING COMPANY, OF MASSILLON, OHIO, A CORPORATION OF OHIO.

WIRE COILING AND CUTTING MACHINE.

1,288,576.

Specification of Letters Patent. Patented Dec. 24, 1918.

Application filed December 8, 1916. Serial No. 135,720.

To all whom it may concern:

Be it known that I, EDISON W. HART, a citizen of the United States, residing at Massillon, in the county of Stark and State of Ohio, have invented certain new and useful Improvements in Wire Coiling and Cutting Machines, of which the following is a specification.

This invention relates to what I shall for convenience term a "wire coiling and cutting machine", the object of the invention being to provide a machine of this character which is rapid and accurate in action and by which the necessary stock can be coiled in an effective manner and cut off into predetermined lengths at desired intervals to form a desired product; for instance a lock washer. This is an article which can be formed with advantage by the machine, although other coiled structures can be produced. Obviously also it is not always necessary that wire be employed for the stock to be coiled may be of any suitable nature.

In the drawings accompanying and forming part of the present specification I have shown in detail one convenient form of embodiment of the invention, which I will set forth fully in the following description to enable those skilled in the art to practice the invention. I do not restrict myself to this exact disclosure, however; I may depart therefrom in several respects within the scope of the invention defined by the claims following said description.

35 Referring to said drawings:

Figure 1 is a side elevation of the machine.

Fig. 2 is a vertical sectional elevation of Fig. 1, looking toward the left and with 40 parts broken away.

Fig. 3 is a side elevation of the lower rear portion of the machine and as seen from the right in Fig. 2.

Fig. 4 is a front elevation.

45 Fig. 5 a side view, and

Fig. 6 a plan view of coiling means, detail views of which will hereinafter be more particularly described.

Fig. 7 is a detail view of portion of the 50 pawl and ratchet means.

Like characters refer to like parts throughout the several views, which are on different scales.

The framework for carrying the different parts of the machine may be of any suitable character. That shown comprises in its construction the base or bed 2 and the column or upright 3 rising therefrom, the two being united in any desirable manner as by bolts 4, of which there may be any proper number. The column 3 near its lower end is cut away to produce a practically flat surface as 5 to which is bolted or otherwise suitably connected the table 6 which directly supports the coiling means.

In the present case the coiling means comprises a head as 7 and a mandrel as 8. This head and mandrel are both normally fixed, being disposed at right angles or practically so to each other. The head 7 has the slot 9 open at the front to receive the mandrel 8, the mandrel extending oppositely from the slot. Generally speaking this particular construction is somewhat similar to that disclosed in Letters Patent No. 1,213,480, granted to me January 23, 1917 and to which reference may be had. The mandrel 8 is rigidly held by a chucking element as 10 in the upright portion of the bracket 11 fastened as by screws 12 to the table 6. From this it will be clear that by taking out said screws the mandrel 8 with a piece of stock coiled about it can be removed through the open front end of the slot 9. The coiling head 7 is suitably rigidly fastened to the carrier or block 13 adapted to be clamped as by the clamping member 14 to the table 6. The coiling head 7 has a chamber 15 adjacent to and intersected by the open ended slot 9, the wall of this chamber being separated from the wall of the slot 9 a distance practically agreeing with the thickness of the stock and acting to coil the stock or wire 17 about the mandrel 8 as the stock or wire is advanced. In the present case the feed or forward movement of the stock as will hereinafter appear, is obtained automatically or at least mechanically. The wire is moved in the direction of the arrow in Fig. 5 and striking the wall of the chamber 15 is 110

caused by said wall to be coiled about the cylindrical mandrel, the mandrel defining the internal diameter of the coiled structure. On the coiling head 7 is a fixed blade 18 which serves as a suitable gage to regulate the pitch of the coiled or helical structure. Such a blade or gage member is also set forth in my prior application.

The wire is fed from a reel and initially 10 passes under the action of straightening rollers, leaving the latter and being grasped by feed rollers which conduct the same positively yet intermittently to the mandrel or coiling mechanism of which the mandrel 15 forms a part. I will now describe an arrangement of straightening and feeding rollers which has been found satisfactory. To the table 6 is bolted or otherwise secured a bracket 19 which acts as a convenient support 20 for the feed rollers to which I have already referred. Bolted or otherwise conveniently connected with the bracket 19 is an extension 20 which acts suitably to support the two groups of rollers 21 and 22, the 25 axes of the rollers 21 being transverse to those of the rollers 22. The groups of rollers are disposed in coöperating pairs and are peripherally grooved. They guide and straighten the wire 17 after the wire passes 30 through the guide element 23' mounted on the extension 20. As shown the coöperating pairs of rollers 21 turn about vertical axes, the coöperating pairs of rollers 22 being movable about horizontal axes. 35 Although the rollers coöperate in pairs, they are shown as staggered. The wire from the reel as will be clear, is first passed between the sets of rollers of the group 21 and then between the sets of rollers 40 of the second group 22 where it is received between the feed rollers 23 and 24 which are positively and intermittently driven. These rollers 23 and 24 are practically in the form of disks and the lower roller has a circumferential groove virtually midway between its sides to receive the wire 17 as best 45 illustrated in Fig. 2. The roller 23 as shown is fastened to the shaft 25, while the roller 24 is fastened to a practically similar superposed shaft 26, the two shafts being supported by suitable bearings in the bracket 19. The bearings 27 for the upper shaft 26 may be adjusted as by screws 28 and 29 to 50 compensate for wear, the screw 29 being furnished with a hand wheel 30 (Fig. 2) to facilitate its adjustment. Keyed or otherwise suitably connected with the shaft 25 is a spur gear 31 in mesh with a companion spur gear 32 fastened as by keying to the upper shaft 26. The lower shaft 25 as will hereinafter appear is positively driven, and it will be 55 clear that when it is thus operated it effects a similar action through the intermediate

gears 31 and 32, to effect the simultaneous and proper rotation of the feed rollers or 65 disks 23 and 24 to positively advance the stock 17.

Fastened as by keying to the shaft 25 is a ratchet wheel 33. The shaft 25 loosely supports between the ratchet wheel 33 and the 70 bracket 19 the rocker or arm 34 which has a pivoted connection with the lower end of the pitman 36, the stroke of which can be adjusted as will hereinafter more particularly appear, to regulate the degree of movement of the rocker or oscillating arm 34 and therefore of the pawls 37, 38 and 39 pivotally supported upon the rocker. These pawls coöperate with the toothed periphery of the ratchet wheel 33. By this adjustment 75 as will be clear, the amount of stock to be advanced by the rollers or feed disks 23 and 24 through the intermediate parts can be adjusted and a similar observation applies to the structure to be coiled. The points or 80 teeth of these pawls are so disposed that each engages a coöperating ratchet tooth at a different point in the length thereof, the result being that at least one pawl as shown for instance by that on the left in Fig. 7 85 90 will always be behind the radial part of a ratchet tooth to insure always the proper intermittent movement of the ratchet wheel 33. It will be clear, of course, that on the downward motion of the rocker 34 the feed 95 rollers or disks 23 and 24 will be rotated so as to feed forward a definite length of stock which is projected into the chamber 15 and is coiled by the wall thereof about the mandrel 8 in the manner already described. The 100 pawls 37, 38 and 39 are maintained in engagement with the periphery of the ratchet wheel 33 by springs as 40 connected therewith and also to a loop or eye 41 fitted freely around the shank of the screw 42 tapped or 105 otherwise fitted into the outer end of the shaft 25 as illustrated in both Figs. 1 and 2, the head of said screw 42 preventing accidental displacement of the loop or eye 41.

The main shaft of the machine is designated by 43 and as shown it is supported by suitable bearings on the upper end of the column or upright 3. This shaft may be driven in any desirable manner as by the pulley or drum 44 loose thereon and adapted to be engaged with the shaft as desired through the agency of a clutch 45 operated by the rod 46 which in turn is actuated by the hand lever 47 (Figs. 2 and 3). It will be clear that when the pulley 44 is in motion and 115 120 that when it is clutched to the shaft 43, the latter will be rotated. As shown the shaft is provided with a disk 48 rigid therewith, the exterior enlargement 49 of the disk having a T-slot 50 to receive the correspondingly shaped head 51 of the bolt 52, this bolt 125

extending through a bushing 53 in the upper end of the pitman 36 and constituting a means for pivotally connecting the pitman to the disk 48 or equivalent driver. The enlargement 49, it will be noted, extends radially of the disk 48 and crosses the center of motion thereof for a reason that will herein-after appear. The T-head 51 is interiorly threaded to receive the screw 54 by which the bolt or pivot pin 52 can be adjusted radially of the disk 48 to regulate the degree of movement of the pitman 36. Before effecting this adjustment it will be necessary to un-loosen the nut 55 of the bolt and after the adjustment is accomplished said nut will be set. The adjusting screw 54 has a swiveled connection with the plates 56 and 57 closing the opposite ends of the T-slot 50, these plates 56 being held in position against the enlargement 49 by screws as 58. The said adjusting screw 54 may as shown be furnished with a head 59 shaped to receive a wrench or equivalent tool to effect its rotation and the consequent adjustment in stroke of the pitman 36 and parts actuated thereby.

The machine is provided with a suitable cutter or knife which in the present case is automatic in action and which is so timed as to cut through the coiled stock on the completion of each helix, the result being the production of parts that are suitable for lock washers. Such a cutter as meets my conditions is that denoted by 60. The cutting edge of this cutter is longitudinally convex. This cutter as shown is rigid with the carrier 61 connected with the block 62 having a tongue and groove connection with a practically similar block 63 rigid with the head 64 which is gibbed to the forward side of the column or upright 3 in vertical line with the bracket 13. The cutter head 64 has a spherical capped pocket 65 to receive the ball 66 on the lower section of the sectional pitman 67, the ring or band 68 of the upper section of the pitman fitting the eccentric 69 on the intermediate portion of the main or power shaft 43. In view of this condition it will be clear that on each rotation of the shaft 43 the head 64 through the intermediate parts is given one full reciprocation. When the head is in its retracted position the knife or cutter 60 will be above the stock coiled on the mandrel 8. On the advance of the head 64, however, the cutter 60 will be carried therewith and its cutting edge will be caused to cut through the foremost whirl of the stock coiled on the mandrel 8. As will be understood, the stock 17 will be advanced on the down stroke of the rocker 34 and on each of such strokes sufficient stock is fed forward to produce a complete helix. The parts are so timed that just before the rocker 34 commences its

backward movement during which the pawls 37, 38 and 39 are ineffective, the head 64 is reciprocated in the manner set forth to obtain the cut piece.

In my prior Letters Patent which I have already identified, I alluded to the importance of the means for receiving the thrust of the knife or cutter. In that application this thrust was received by the coiling head which in a measure is like that denoted by 7 in the present case. In some instances this is a proper construction, but it will not answer always, because in certain cases it is practically requisite that the shock be taken from the coiling head and the mandrel as well. I secure this particular condition by what I term a "jack support" as which as shown consists of two elements in threaded connection with each other to provide for the necessary longitudinal adjustment. This jack support is sustained upon the table or plate 6 and the forward or outer end of the coiling head 7 rests on it as clearly shown in said Fig. 3. The result of this is that no matter how heavy the stock may be or how powerful the blow of the cutter or knife 60, this although received by both the forming head 7 and mandrel 8 is transferred to the jack support 70 and in turn to the framing of the machine without possibility of fracturing the forming head or mandrel. I find this to be a very important feature and although it is broadly suggested in my prior application, as will be inferred, still in the present instance I have provided more effectual and desirable means for preventing the possible breakage of any of the parts.

What I claim is:

1. In a machine for wire coiling and cutting in the production of lock washers, the combination of a coiling head, means for intermittently feeding wire stock to the head, the head having means to coil the stock, an automatically operative cutter to cut off a single coil of the coiled structure during each period of rest to thus present a spring washer, and a longitudinally adjustable support under the coiling head to take the thrust of the cutter.
2. In a machine for wire coiling and cutting in the production of lock washers, the combination of a coiling head, means for intermittently feeding wire stock to the head, the head having means to coil the stock, an automatically operative cutter to cut off a single coil of the coiled structure during each period of rest to thus present a spring washer, and a longitudinally adjustable support under the coiling head to take the thrust of the cutter, the machine having a fixed part which carries said support.
3. In a machine for wire coiling and cut-

ting in the production of lock washers, the combination of a coiling head and a co-operative mandrel, means for presenting wire stock to the mandrel, the head having 5 means to coil the stock on the mandrel, a cutter, means acting against the cutter to cause the same to cut off a single coil while on the mandrel to produce a lock washer, and a jack support under the free end of 10 the head, the machine having a fixed part

which carries the support, the latter receiving the thrust of the cutter which is applied to the mandrel and the head and transferring the same to said fixed part.

In testimony whereof I affix my signature 15 in the presence of two witnesses.

EDISON W. HART.
